UNITED STATES PATENT OFFICE.

JOHN B. GOODWIN, OF PROVIDENCE, RHODE ISLAND, ASSIGNOR TO
WILLIAM P. GOODWIN, OF SAME PLACE.

FOLDING AND SWINGING GATE.

SPECIFICATION forming part of Letters Patent No. 381,065, dated April 10, 1888.

Application filed October 12, 1887. Serial No. 252,101. (No model.)

To all whom it may concern:

Be it known that I, JOHN B. GOODWIN, of Providence, in the county of Providence and State of Rhode Island, have invented certain new and useful Improvements in Folding and Swinging Gates, of which the following is a full, clear, and exact description, reference being had to the accompanying drawings, forming part of this specification.

This invention relates to swinging, collapsible, or folding gates or guards, and is designed as an improvement on the especial class of gates particularly described and fully illustrated in United States Letters Patent No. 369,284, issued to me August 30, 1887, and to which particular reference is hereby made in construing this application.

The especial object of my invention is to provide a collapsible swinging gate which may in its action automatically lock and unlock the swinging part thereof, so that when the gate is in extended or closed position the swinging parts are rendered practically immovable, and when the gate is in folded or open position the swinging parts can be freely operated.

To the aforesaid purpose my invention consists, essentially, in providing the swinging parts or section with a trip-locking device which is engaged and operated by the moving hanger supporting the gate, and which is appropriate to lock the swinging section to the fixed framing when the gate is in extended position.

In order that my invention may be fully understood, I have illustrated in the accompanying drawings, and will proceed to describe with reference to the aforesaid patent, the best forms of the device so far devised by me, with the knowledge that such forms admit of constructional modifications.

In the accompanying drawings, Figure 1 is a vertical central sectional view of a portion of a swinging folding gate, as will be understood upon referring to the above-cited patent, and which is shown as provided with my trip-locking device. The section is taken on line 1,1 in Fig. 2. Fig. 2 is a top plan view of the parts shown in Fig. 1. Figs. 3 and 4 are vertical central sectional views of portions of the gate, and show, respectively, two different forms of my improved locking device.

In the said drawings like numbers of reference designate corresponding parts throughout.

Referring to the drawings, 22 is the fixed framing, having the track 20 for the roller-hanger 17 to run on. This hanger consists in a track having the wheels 18, and provided with the anti-friction rolls 19. The connecting-rod 16 is designed to support a gate swung from below, as shown in the aforesaid patent. The swinging section or bracket 23 is secured to and turns with the hinge-bar 14, and is provided with a sufficient portion of the track 20 to receive the hanger 17. This swinging section or bracket 23 is formed with a horizontal support-flange, 25, which slides over the upper face of the horizontal shelf or extension 26 constructed on the framing 22.

The foregoing described parts are constructed substantially like the same parts shown in the above-referred-to patent and operate in the same manner.

The scheme of this invention is to lock the swinging section 23 immovably to the fixed framing when the gate is extended or opened. In order to accomplish this I pivot the lever-arm 35 at 36 to the ears 37, formed on the upper side of the flange 25. One end of the lever-arm is normally pressed upward by the subjacent spring 38, set in the socket 39 of the flange 25.

In Fig. 1 this lever-arm 35 is L-shaped, with one arm thereof depending and provided with the trip 40 and the latch part 41. This depending part extends down through the slot 42, formed in the flange, and also through the slot 43, formed in the fixed shelf 26, and this latter slot is made approximately L-shaped in plan view, as seen in Fig. 2 in dotted lines.

The trip 40 is arranged so as to be struck by the part 44 of the hanger when the latter is run onto the track 20 of the swinging section or bracket 23, and this action will prevent the latch 41 from locking in the slot 43, as it would otherwise do. When the hanger is moved off the track formed on the hanger 23, the latch 41 of the locking device will obviously lock in the slot 43, and so prevent the swinging section or bracket 23 from being swung on its bearings.

In the form shown in Fig. 3 the lever-arm

35 is a straight pivoted bar having one end engaged by the spring 38, tending to press it upward, and the other end formed with the latch or plug 41, which passes down through 5 the slot 42 in the flange 25 and locks in the slot 43, formed in the shelf 26. The lever-arm is forced upward, so as to unlock, by virtue of the trip or pin 40, which reciprocates vertically through the perforations 45 and 46, formed in 10 the flange 25 and the shelf 26, respectively, being forced upward by the part 44 of the hanger 17 striking the foot of the trip and sliding thereunder. The loose trip-pins 40 in 15 Figs. 3 and 4 are formed with collars 47, to prevent them from dropping through the openings 45 and 46.

In the construction shown in Fig. 4 the lever-arm 35 is a flat spring-strip secured at one end by the screws 48, while the free end of the 20 strip has an eye in which is suspended the head of the latch or plug 41. The resiliency of the strip tends to press the latch into locking engagement with the slot 43, and whenever the hanger is out of engagement with the 25 foot of the trip 40 this locked position will be assumed. When the trip 40 is pushed up by the hanger, the spring 35 will be forced into the position shown in Fig. 4, thereby unlocking the swinging portion from the fixed and 30 allowing the former to be free.

The locking devices are each shown as covered by the casing or housing 49, which screens the parts from dirt.

Having thus described my invention, I claim 35 as new and desire to secure by Letters Patent—

1. In a gate of the class described, the combination, as hereinbefore set forth, with a rolling hanger for supporting the gate, and a track for the hanger provided with a swinging section or bracket forming part of the track, and the fixed framing, of a trip-locking device engaged and actuated by the moving hanger and appropriate to lock the swinging section or bracket and the fixed framing together when 45 the gate is extended, as and for the purpose herein described.

2. In a gate of the class described, the combination, as hereinbefore set forth, with a traveling hanger for supporting the gate, and 50 a track for the hanger provided with a swinging section or bracket comprising part of said track, and the fixed framing, of a trip-locking device mounted on the swinging section or bracket and engaged and operated by the 55 moving hanger and appropriate to lock the swinging section to the fixed portion or framing when the gate is in closed or extended position, substantially as and for the purpose herein described.

60 3. In a gate of the class described, the combination, as hereinbefore set forth, with the rolling hanger for suspending the gate, and the track for the hanger provided with a swinging section or bracket composing part 65 of the said track, and the fixed framing, of a

trip-locking device comprising a spring-acted lever-arm mounted on the swinging section and having a trip, and engaged by the traveling hanger and a latch appropriate to lock the swinging section to the fixed framing, as 70 and for the purpose herein described.

4. In a gate of the class described, the combination, as hereinbefore set forth, with a traveling hanger for suspending the gate, and the track for the hanger provided with the 75 swinging section comprising a part of said track, the said section or bracket provided with a slotted support-flange, and the framing provided with a slotted extension or shelf engaged by the said flange, the trip-locking device mounted on the said support-flange and extending down through the slots of the flange and the extension or shelf, and appropriate to be tripped by the rolling hanger and to lock with the fixed framing, substantially as and 80 for the purpose herein described.

5. In a gate of the class described, the combination, as hereinbefore set forth, with the traveling hanger and the track therefor provided with a swinging section or bracket comprising a part of said track, the fixed framing provided with the slotted shelf or extension, and the slotted support-flange upon the said swinging section and engaging the said shelf or extension, of the trip-locking device mounted on 90 the support-flange and engaged and actuated by the hanger and appropriate to lock with the shelf or extension, and the casing or housing for covering the said locking device, substantially as and for the purpose herein described. 95

6. The combination, with the framing 22, provided with the slotted extension 26, the swinging section 23, provided with the slotted support-flange 25, the rolling hanger 17 for supporting the gate, and the track 20 therefor, of a trip-locking device for locking the swinging section and the fixed framing together, the said device automatically operated by the rolling hanger, substantially as and for the purpose herein described. 100 105

7. The combination, with the framing 22, provided with the slotted extension 26, the hinge-bar 14, and the swinging section or bracket 23, provided with the slotted support-flange 25, the rolling hanger 17 for supporting 110 the gate, and the track 20 for the hanger, of the spring-acted lever-arm 35, provided with the trip 40, engaged by said hanger and having the latch 41 for locking the said swinging section to the framing, substantially as and 115 for the purpose herein described.

8. The combination, with the swinging section and the trip-locking device mounted thereon, substantially as described, of the casing 49 for housing the said device, substantially 120 as described.

JOHN B. GOODWIN.
